TUBING AND WELL TOOL COUPLING

Reuben C. Baker, Coalinga, Calif., assignor to
 Baker Oil Tools, Inc., Vernon, Calif., a corpora-
 tion of California

Application November 4, 1946, Serial No. 707,664

20 Claims. (Cl. 166—1)

1

The present invention relates to devices for coupling parts of well tools together.

Certain well tools are positioned in a well bore or casing and have a threaded member adapted for connection to a tubular string. The tubular string is run in the well hole to the location of the well tool and is rotated to thread it into the latter member. In many instances, the well bore is not vertical, which renders difficult the proper alignment of the tubular string with the tool preparatory to the screwing of the string into the tool. As a matter of fact, misalignment between the parts often prevents them from being threadedly connected at all.

In addition to the foregoing difficulty of obtaining proper alignment, another disadvantageous operating condition is encountered. The connection between the tubular string and well tool is usually provided by mating left-hand threads to permit unscrewing of the tubular string from the well tool upon right-hand rotation of the string. This rotational direction and left-hand thread are chosen to prevent unthreading in the joints comprising the tubular string. However, although the joints are tightened upon unscrewing of the tubing string from the well tool, the threading of the former into the latter can occur only upon left-hand rotation of the tubing string, which may produce loosening or unscrewing of the string at one or more joints along its length.

Accordingly, it is an object of the present invention to provide an improved coupling, which is operable to effect a threaded connection between a tubular string and a well tool without the necessity for rotating the tubular string, thus obviating any need for turning the string in a left-hand direction.

Another object of the invention is to provide an improved coupling, which is operable to effect a threaded connection between a tubular string and a well tool despite misalignment between the latter members.

A further object of the invention is to provide a coupling for effecting a threaded connection between a tubular string and a well tool by non-rotatably moving the string into the tool, disconnection between the two being effected by rotation of the tubular string.

Yet another object of the invention is to provide a coupling between a tubular string and a well tool, in which the coupling comprises a laterally movable threaded element on one member held positively in mating engagement with the cooperable threads on the other member by the stress imposed on the tubular string.

2

Forms which the invention may assume are exemplified in the following description and illustrated by way of example in the accompanying drawings, in which:

5 Figs. 1, 2 and 3 are longitudinal sections through a tubing and well tool, illustrating the coupling device in different operative positions.

Fig. 4 is a cross-section taken along the line 4—4 on Fig. 2.

10 Fig. 5 is a longitudinal section through a well packer and tubing string coupled thereto.

Fig. 6 is a longitudinal section through a tubing string and coupled collar forming part of a casing string.

15 The invention is disclosed in the Figs. 1 to 5, inclusive, embodiment as effecting a connection between a tubular string of tubing or drill pipe A and a well packer B anchored in a well casing C. The packer includes a tubular body 10 held against upward movement in the casing C by an upper expander 11 wedged into an upper set of segmented slips 12 engaging the wall of the casing; the body being prevented from moving in a downward direction by a lower expander 13 wedged into a lower set of segmented slips 14 engaging the wall of the casing. The downward thrust between the body 10 and expander 13 may be transmitted through a split tapered lock ring 15 wedged into a tapered groove 16 in the lower expander. A seal between the packer body and casing is provided by a packing sleeve 17 compressed between the upper and lower expanders 11, 13 and expanded outwardly into sealing engagement with the casing wall.

35 The upper end of the packer body 10 has a box 18, or female member, provided with a thread 19, and preferably a left-hand thread, which may be a square thread or any other suitable configuration. The tubing string A is adapted to

40 be coupled to the packer body 10 by means of a coupling or latching device mounted on the tubular string. The lower end of the tubular string includes a two part member comprising an upper sub 20 threaded onto a lower sub 21 which has

45 an expander 22 on its exterior around which a split, externally threaded latch ring or sleeve 23 is disposed. The expander 22 has an external tapered surface 24 inclined toward the longitudinal axis of the tubing string in an upward direction, and the latch ring or sleeve 23 has a corresponding tapered inner surface 25 for engagement by the expander.

50 A longitudinally extending key 26 is suitably secured, as by welding material 27, to the lower sub 21, projecting between the opposed spaced ends 28, 29 of the latch ring. The key 26 extends

outwardly a sufficient distance to insure its engagement with one or both ends 28, 29 of the latch ring 23 irrespective of the lateral position of the ring on the member 21. The key, however, does not project outwardly from the axis of the tubing string sufficiently to engage the threads 19 on the box end 18 of the packer body 10.

The latch ring 23 has spring-like properties, tending to expand outwardly inherently to a limited extent. The latch ring may move longitudinally with respect to and along the tapered surface 24 of the expander 22, its upward movement being limited by its engagement with a shoulder 30 provided by the lower end of the upper sub 20. The expansion of the latch ring due to its own inherent expansible properties is insufficient to produce its dropping from the lower sub 21 during movement of the tubing string A within the well casing toward or away from the packer B.

To facilitate expansion and contraction of the split latch sleeve 23, longitudinal grooves 31 may be cut or otherwise formed part way into its exterior surface. It is to be noted that the thread 32 on the exterior of the latch sleeve has the same pitch as the mating thread 19 in the box end of the packer body, and that the leading faces 33 of these threads are tapered in a downward and inward direction, whereas their trailing faces 34 correspond to the faces on the square threads 19. In effect, the threads 32 are of general buttress configuration.

Let it be assumed that well packer A has been anchored in the well casing C by suitable means, such as a string of tubing (not shown), which was coupled to the packer body 10 by means of its usual left-hand thread engaging the left-hand thread 19 in the body. Following setting of the packer in packed-off condition, this tubing string (not shown) may be rotated to the right and unscrewed from the packer body, and then removed from the well bore.

At some later time, it may be desired to couple a tubular string to the packer. The tubular string A, with its coupling or connecting device at its lower end, is run in the well casing until it reaches the upper end of the packer body 10. The range of inherent outward expansion of the latch ring positions its buttress thread 32 laterally beyond the packer body threads 19 by a slight amount, causing its engagement with the upper end of the body 10, as the lower sub 21 is piloted or moved into the upper end of the box 18 (Fig. 1). Such engagement holds the latch ring 23 in an upper position until the continued lowering of the tubular string engages the shoulder 30 with the upper end of the latch ring and forces or pushes the latter into the threaded box 18, the tapered leading faces 33 on the ring thread 32 causing the ring to be retracted inwardly as the external threads 32 ratchet over the internal box threads 19. Such inward ratcheting is permitted because of the space 35 which exists between the inner surface 25 of the latch ring and the tapered outer surface 24 on the expander 22 (see Figs. 1 and 2).

Downward movement of the lower sub 21 and connected upper sub 20, with the latch ring 23 mounted thereon, within the threaded box 18, is limited by engagement of the tapered upper shoulder 36 on the sub 20 with the tapered end 37 on the packer body 10. Following their engagement, the ring 23 inherently expands outward to place its threads 32 in engagement with the box threads 19 (Fig. 3). Thereafter, an up-

ward strain may be taken on the tubing string A to pull the two part member 20, 21 upwardly within the latch ring 23, which is held against upward movement by virtue of engagement of the upper faces 34 of its threads with the lower faces of the square threads 19 in the box 18. This upward movement causes the tapered surface 24 on the expander portion 22 of the lower sub 21 to engage the companion tapered surface 25 on the latch ring 23 and hold the latter wedged outwardly into firm and full mating engagement with the threads 19 in the box end of the packer body (Fig. 5).

The load carrying capacity of the apparatus, including the latch ring or sleeve 23, is sufficient to permit a substantial upward pull or thrust to be taken on the tubing string A, and this pull is transmitted to the packer body 10 through the co-engaging tapered surfaces 24, 25 and mating threads 32, 19 on the latch ring 23 and box 18. From the body 10, the upward pull is transmitted to the casing C through the lower abutment 38 threaded on the packer body 10, lower slips 14, lower expander 13, packing sleeve 17, upper expander 11 and upper slips 12, whose wickers 39 are embedded in the casing.

In the event that it is desired to release the tubing string A from the packer B, it is lowered a slight distance to relieve the wedging force of the expander 22 from the latch ring 23. Such lowering may continue until the upper sub shoulder 30 engages the upper end of the ring, leaving a lateral space 35 between the inner surface of the ring and the outer surface of the expander (as in Fig. 3). The tubing string may now be rotated to the right, such rotation being transmitted to the latch ring 23 by engagement of the key 26 with one of the ends 29 of the latch ring. As the latch ring rotates in a right-hand direction, it is threaded upwardly from the box 18 until it is completely disengaged from the packer body 10. Such complete unthreading or uncoupling of the latch ring 23 permits the entire tubing string A to be elevated and withdrawn from the well casing C and bore.

In Fig. 6, the coupling F is applied to a tubing string A connectable to a float collar D forming part of a casing or liner string E. The collar D is disclosed as provided with a body 40 of cementitious material, having a central tubular member 41 provided with a female left-hand threaded box 42 at its upper end. The central passage 43 through the collar communicates with lateral ports 44 extending through the collar to its exterior. A ball valve 45 may be included in the collar which opens the passage 43 upon movement in a downward direction and rises into engagement with a seat 46 in the central passage to prevent upward flow of fluid therethrough.

Assuming that the casing string E has been run into a well bore, the tubing string A with the coupling device F at its lower end may then be run downwardly through the well casing C to effect a coupling with the upper threaded portion 42 of the collar simply by stabbing the lower end 22 of the tubing string into the central tubular member 41 of the collar. As explained in connection with the well packer application of the invention, the latch ring 23 contracts and rides over the threads 47 in the box 42 until it is disposed completely therewithin, whereupon an upward strain taken on the tubing string A holds the latch threads 32 firmly in engagement with the box threads 47 in the collar D. If desired, a suitable side seal 48 may be provided in

the lower sub 21 for engagement with the inner surface of the collar member passage 43, to prevent leakage of fluid therebetween.

One use of the tubing string and collar arrangement A, D disclosed in Fig. 6 resides in cementing the casing string E in place after it has been run in the well bore. The cement slurry may be pumped downwardly through the tubing string A for discharge through the side ports 44 in the collar and for upward passage through the annulus between the casing string and wall of the hole. Following completion of the cementing operation, the tubing string A may be rotated to the right to unscrew the latch ring 23 from the collar box 42, permitting the tubing string to be removed upwardly from the well bore. As is well known, the ball valve 45 moves upwardly to engage its seat 46 and prevent return flow of the cement slurry into the casing E.

By virtue of the coupling device disclosed, a threaded connection may be effected in the well bore itself between the tubing string and a well tool without rotating the tubing string. Since the threads in the well tool are preferably left-hand, such rotation, if required, would ordinarily necessitate the left-hand rotation of the tubing string, in order to thread the male member downwardly into the threaded box. Because of the fact that no rotation is required to accomplish the threaded coupling between the latch ring 23 and the box 18 or 42, it is obvious that the danger of unscrewing the tubing joints at some point along its length is entirely eliminated. However, when it is desired to release the tubing string from the well tool, the former is rotated in a right-hand direction to unthread the latch ring from the box. This direction of rotation tends to tighten the tubing string joints, rather than to loosen the same.

In view of the ability of the coupling device to move laterally to a limited extent, misalignment between the lower end of the tubing string and the cooperable box does not preclude proper threaded engagement of the latch device in the cooperable well tool. The tubing string need only be stabbed longitudinally downwardly into the box and the threaded latch member 23 will shift inwardly a sufficient extent to permit its complete insertion into the box 18 or 42, whereupon the tubing string A may be moved upwardly to wedge the threaded male latch member 23 firmly into the cooperable threads 19 or 41 on the box. The specific design shown by way of example in the drawings insures that proper mating between the threaded members will remain so long as an upward strain is imposed on the tubing string.

While I have shown preferred forms of my invention, it is to be understood that various changes may be made in their construction by those skilled in the art without departing from the spirit of the invention as defined in the appended claims.

Having thus described my invention, what I claim and desire to secure by Letters Patent is:

1. An apparatus of the character described, including a well tool having a thread, a member adapted to be connected to said tool, an expandable and retractable latch ring carried by and movable laterally on said member and also longitudinally relative to said member, said ring having a thread companion to said well tool thread and engageable therewith, said ring being adapted to move laterally in one direction on said member into threaded engagement with said

well tool thread and laterally in the other direction on said member to an extent sufficient to bring said threads out of engagement with each other to enable said ring to be moved longitudinally and without rotation past said well tool thread, said member being provided with actuating means engageable with said ring and movable longitudinally with said member relative to said ring for moving said ring laterally of said member in one of said directions.

2. An apparatus of the character described, including a well tool having a thread, a member adapted to be connected to said tool, an expandable and retractable longitudinally split latch ring carried by and movable laterally and longitudinally on said member, said ring having spring-like properties and provided with a thread companion to said well tool thread and engageable therewith, said ring being adapted to move laterally in one direction on said member into threaded engagement with said well tool thread and laterally in the other direction on said member to an extent sufficient to bring said threads out of threaded engagement with each other to enable said ring to be moved longitudinally and without rotation past said well tool thread, said ring and said member being provided with actuating means engageable with said ring and movable longitudinally with said member relative to said ring for moving said ring laterally of said member in one of said directions.

3. An apparatus of the character described, including a well tool member having a thread, a companion member adapted to be connected to said tool member, an elastic expandable and retractable latch ring movable laterally on said companion member and provided with a thread companion to said well tool member thread, said ring being movable laterally on said companion member to an extent sufficient to bring said threads out of threaded engagement with each other to enable said ring to be moved longitudinally and without rotation past said well tool member thread, means on said companion member cooperable with said latch ring to hold said latch ring thread in engagement with said well tool member thread, and coengaging means on said ring and one of said members for moving said ring laterally of said companion member.

4. An apparatus of the character described, including a well tool member having a thread, a companion member adapted to be connected to said tool member, an elastic expandable and retractable latch ring movable laterally on said companion member and provided with a thread companion to said well tool member thread, said ring being movable laterally on said companion member to an extent sufficient to bring said threads out of threaded engagement with each other to enable said ring to be moved longitudinally and without rotation past said well tool member thread, means on said companion member cooperable with said latch ring to hold said latch ring thread in engagement with said well tool member thread, means providing a rotatable driving connection between said companion member and latch ring, and coengaging means on said ring and one of said members for moving said ring laterally of said companion member.

5. An apparatus of the character described, including a first member adapted to be positioned in a well bore and having a thread, a second member adapted to be connected to said first member, an expandable and retractable latch ring movable longitudinally and laterally on said second mem-

ber, said ring having a thread companion to said thread on said first member and engageable therewith, said ring being adapted to move laterally in one direction on said second member into threaded engagement with said first member thread and laterally in the other direction on said second member to an extent sufficient to bring said threads out of engagement with each other to enable said ring to be moved longitudinally and without rotation past said first member thread, said second member being provided with actuating means engageable with said ring and movable longitudinally with said second member relative to said ring for moving said ring laterally of said second member in one of said directions, and means providing a rotatable driving connection between said second member and latch ring.

6. An apparatus of the character described, including a first member adapted to be positioned in a well bore and having a female thread, a second member adapted to be piloted within said first member while said first member is in said well bore, an expansible and retractable latch ring carried by and movable longitudinally and laterally on said second member, said ring having a male thread engageable with said female thread, said ring being adapted to move in a lateral outward direction on said second member into threaded engagement with said female thread and in a lateral inward direction on said second member to an extent sufficient to bring said threads out of engagement with each other to enable said ring to move longitudinally and without rotation past said female thread, said second member being provided with actuating means engageable with said ring and movable longitudinally with said second member relative to said ring for moving said ring laterally of said second member in one of said directions.

7. An apparatus of the character described, including a well tool having a female thread, a member adapted to be positioned within said tool, a retractable inherently expansible latch ring carried by and movable laterally on said member and provided with a male thread engageable with said female thread, said ring tending, by itself, to remain in an outward expanded condition with its male thread in meshing engagement with said female thread, said ring being adapted to move in a lateral outward direction on said member into threaded engagement with said well tool thread and in a lateral inward direction on said member to an extent sufficient to bring said threads out of engagement with each other to enable said ring to be moved longitudinally and without rotation past said well tool thread, said member being provided with actuating means engageable with said ring and movable longitudinally with said member relative to said ring for moving said ring laterally of said member in one of said directions.

8. An apparatus of the character described, including a well tool member having a female thread, a second member adapted to be positioned within said tool member, a retractable longitudinally split inherently expansible latch ring movable laterally on said second member and provided with a male thread engageable with said female thread, said ring tending, by itself, to remain in an outward expanded position with its male thread in meshing engagement with said female thread, said ring being retracted on said second member to the extent in which the effective outer diameter of said male thread is less than the inner

diameter of said female thread, said ring being provided with cam means, and coacting means on one of said members adapted to engage said cam means to retract said ring, whereby to disengage said male thread from said female thread upon relative longitudinal movement between said members.

9. An apparatus of the character described, including a well tool member having a female thread, a second member adapted to be positioned within said tool member, a retractable longitudinally split inherently expansible latch ring movable laterally on said second member and provided with a male thread engageable with said female thread, said ring tending, by itself, to remain in an outward expanded position with its male thread in meshing engagement with said female thread, said ring being retracted on said second member to the extent in which the effective outer diameter of said male thread is less than the inner diameter of said female thread, said ring being provided with cam means, coacting means on one of said members adapted to engage said cam means to retract said ring, whereby to disengage said male thread from said female thread upon relative longitudinal movement between said members, and means providing a rotatable driving connection between said second member and latch ring.

10. An apparatus of the character described, including a well tool member having a female thread, a second member adapted to be positioned within said tool member, a retractable longitudinally split inherently expansible latch ring carried by and movable laterally on said second member and provided with a male thread engageable with said female thread, said ring tending, by itself, to remain in an outward expanded condition with its male thread in meshing engagement with said female thread, said ring being retractable on said member to the extent in which the effective outer diameter of said male thread is less than the inner diameter of said female thread, said second member being provided with actuating means engageable with said latch ring and movable longitudinally with said second member relative to said latch ring for holding said latch ring outwardly with its thread in engagement with said female thread, said ring being provided with cam means, and coacting means on one of said members adapted to engage said cam means to retract said ring, whereby to disengage said male thread from said female thread upon relative longitudinal movement between said members.

11. An apparatus of the character described, including a well tool member having a threaded box, a second member adapted to be positioned within said box, a retractable longitudinally split inherently expansible latch ring carried by and movable laterally on said second member and provided with a male thread engageable with the box thread, said ring tending, by itself, to remain in an outward expanded condition with its male thread in meshing engagement with said box thread, said ring being retractable on said second member to the extent in which the effective outer diameter of said male thread is less than the inner diameter of said box thread, said second member being provided with actuating means engageable with said ring and movable longitudinally with said second member relative to said ring for holding said ring outwardly with its threads in engagement with said box thread, said ring being provided with cam means, coact-

ing means on one of said members adapted to engage said cam means to retract said ring, whereby to disengage said male thread from said female thread upon relative longitudinal movement between said members, and means providing a rotatable driving connection between said second member and latch ring.

12. An apparatus of the character described, including a well tool having a threaded box, a tubular member adapted to be positioned within said box, a retractable longitudinally split inherently expansible latch ring movable laterally on said member, said ring being provided with a male thread engageable with the box thread and having a downwardly diverging tapered inner surface, said ring being retractable on said member to the extent in which the effective outer diameter of said male thread is less than the inner diameter of said box thread, an expander on said member having a downwardly diverging tapered external surface engageable with said tapered surface on said ring to hold said latch ring outwardly with its threads in engagement with said box threads, a longitudinally extending key secured to said member and disposed between the opposed ends of said latch ring to provide a rotatable driving connection between said member and latch ring, and means for moving said ring laterally of said member.

13. An apparatus of the character described, including a first member adapted to be positioned in a well bore and having a thread, a second member adapted to be connected to said first member, an expansible and retractable latch ring movable laterally on said second member, said ring having a thread companion to said thread on said first member and engageable therewith, said ring being movable laterally on said second member to an extent sufficient to bring said threads out of threaded engagement with each other to enable said ring to be moved longitudinally and without rotation past said first member thread, and coengaging cam means on said ring and first member for moving said ring laterally of said second member.

14. An apparatus of the character described, including a first member adapted to be positioned in a well bore and having a thread, a second member adapted to be connected to said first member, an expansible and retractable latch ring movable laterally on said second member, said ring having a thread companion to said thread on said first member and engageable therewith, said ring being movable laterally on said second member to an extent sufficient to bring said threads out of threaded engagement with each other to enable said ring to be moved longitudinally and without rotation past said first member thread, the lower side of the thread on said ring being tapered to engage the thread on said first member to shift the ring laterally out of threaded engagement with said first member upon longitudinal movement of said ring with respect to said first member.

15. An apparatus of the character described, including a first member adapted to be positioned in a well bore and having a female thread, a second member adapted to be piloted within said first member while said first member is in said well bore, an expansible and retractable latch ring movable laterally on said second member, said ring having a male thread engageable with said female thread, said ring being retractile on said second member to the extent in which the effec-

tive outer diameter of said male thread is less than the inner diameter of said female thread, and coengaging cam means on said ring and first member for retracting said ring on said second member to such extent.

16. An apparatus of the character described, including a first member adapted to be positioned in a well bore and having a female thread, a second member adapted to be piloted within said first member while said first member is in said well bore, an expansible and retractile latch ring movable laterally on said second member, said ring having a male thread engageable with said female thread, said ring being retractile on said second member to the extent in which the effective outer diameter of said male thread is less than the inner diameter of said female thread, the lower side of the thread on said ring being tapered to engage the thread on said first member to retract the ring out of threaded engagement with said first member upon longitudinal movement of said ring with respect to said first member.

17. An apparatus of the character described, including a first member adapted to be positioned in a well bore and having a thread, a second member adapted to be connected to said first member, an expansible and retractable latch ring mounted on and movable laterally and longitudinally on said second member, said ring having a thread companion to said thread on said first member and engageable therewith, said ring being movable laterally on said second member to an extent sufficient to bring said threads out of threaded engagement with each other to enable said ring to be moved longitudinally and without rotation past said first member thread, and coengaging cam means on said ring and one of said members for moving said ring laterally of said second member out of threaded engagement with said first member thread.

18. An apparatus of the character described, including a first member adapted to be positioned in a well bore and having a female thread, a second member adapted to be piloted within said first member while said first member is in said well bore, an expansible and retractile latch ring movable laterally on said second member, said ring having a male thread engageable with said female thread, said ring being retractile on said second member to the extent in which the effective outer diameter of said male thread is less than the inner diameter of said female thread, and coengaging cam means on said ring and one of said members for retracting said ring from threaded engagement with said female thread.

19. An apparatus of the character described, including a well tool having a thread, a member adapted to be connected to said tool, an expansible and retractile latch ring carried by and movable laterally on said member and also longitudinally relative to said member, said ring having a thread companion to said well tool thread and engageable therewith, said ring being adapted to move laterally in one direction on said member into threaded engagement with said well tool thread and laterally in the other direction on said member to an extent sufficient to bring said threads out of engagement with each other to enable said ring to be moved longitudinally and without rotation past said well tool thread, said member being provided with actuating means engageable with said ring and movable longitudinally with said member relative to said

ring for moving said ring laterally of said member in one of said directions to hold said ring in threaded engagement with said well tool thread.

20. In apparatus of the character described, including a well tool member having a threaded box, a second member adapted to be connected to said threaded box, a retractable longitudinally split latch ring mounted on and movable laterally of said second member, said ring being provided with a male thread engageable with the box thread and having a downwardly diverging tapered inner surface, said ring being retractable on said second member to the extent in which the effective outer diameter of said male thread is less than the inner diameter of said box thread, said second member being provided with an expander having a downwardly diverging tapered external surface engageable with said tapered surface on said ring to urge said latch ring outwardly with its thread in engagement with said box thread, said ring being provided with cam means, coacting means on one

10

15

20

of said members adapted to engage said cam means to retract said ring, whereby to disengage said male thread from said female thread upon relative longitudinal movement between said members, and a longitudinally extending key secured to said second member and slidably engaging said latch ring to provide a rotatable driving connection between said second member and latch ring.

REUBEN C. BAKER.
